UNITED STATES PATENT OFFICE.

BERNARD LIBERMAN, OF PHILADELPHIA, PENNSYLVANIA.

CIGAR-BUNCHING MACHINE.

1,316,371.

Specification of Letters Patent. Patented Sept. 16, 1919.

Application filed August 15, 1918. Serial No. 249,934.

To all whom it may concern:

Be it known that I, BERNARD LIBERMAN, a citizen of the United States, residing at Philadelphia, in the county of Philadelphia, State of Pennsylvania, have invented a new and useful Cigar-Bunching Machine, of which the following is a specification.

The invention relates to cigar bunching. The object is to provide improved method and means for measuring and disposing the 10 filler to be formed into a cigar bunch so that the bunch shall be of required length when wrapped, without the necessity of cutting off the end, as is now the common practice; improved method and means for distributing 15 the filler forming the bunch to secure a properly shaped cigar, and without waste, and to avoid the possibility of undue packing or compressing of any part of the bunch. My invention also comprises improved 20 method and means for retaining the body of filler in place and to maintain the shape of the bunch during rolling and binding, and improved method and means for measuring 25 and separating the binder from the leaf without wasting. My invention also comprises improvements in details of construction.

Referring to the drawings, which illustrate merely by way of example, suitable 30 means for embodiment of my invention:—

Figure 1 is a plan view of a bunching table showing my invention.

Fig. 2 is a vertical longitudinal section on line 2, 2 of Fig. 1, the apron being omitted.

Fig. 3 is a side elevation.

Fig. 4 is a section on line 4, 4 of Fig. 1.

Fig. 5 is a sectional detail on line 5, 5 of Fig. 1.

Fig. 6 is a perspective view.

Fig. 7 is a fragmentary view of a hook extension of a side forming strip.

Fig. 8 is a section, similar to that shown in Fig. 5 of a strip having a different cross-sectional formation.

Similar numerals refer to similar parts throughout the several views.

Referring to Fig. 1, 9 indicates the bunching table of usual form, 10 the apron and 11 the roller coöperating therewith. The 15 table 9 is provided with the slots 12 for adjustably securing, by means of thumb nuts 13, the beveled guide and forming strips 14 and 15.

It need only be noted that the table 9 20 should be so supported that the underside thereof presents unobstructed and accessible

under surfaces surrounding the slots 12 to permit the free movement of the bolts therein and ready access to the thumb nuts thereon, so that the forming strips may be adjusted easily and conveniently. 60

In the example shown the table is curved or arc shaped with the pivot of the roller to one side thereof. The invention however is equally applicable to a straight table. 65

The forming strips 14 and 15 have the hooked shaped extensions 16 and 17 for projecting into the pocket 18 of the table. These extensions 16 and 17 are correspondingly beveled to form tapered or gradually contracted ends for the pocket 18. These forming strips are of substantial thickness on the outside margins and are beveled down to a thin inner edge or margin flush with the apron, see Figs. 5 and 8. The apron 10 75 is formed and adapted to lie wholly within the inside margins of said forming strips, so that the apron 10 and the flanking forming strips form a substantially continuous bunching surface for rolling the binder 80 about the filler, the beveled formation of the forming strips serving to give the desired tapered formation to the bunch.

It may be noted that while the apron should lie wholly within the inner margins 85 of the forming strips, and the side margins of the apron may lie against the margins of the strips, they should not overlap the same. The margins of the apron may be slightly spaced from the margins of the strips with- 90 out disadvantage.

The forming strips are adjustable as above described to correspond to the dimensions of the bunch and the resulting cigar which it is desired to form. 95

The formation of the hook extensions of the forming strips is such as to provide in combination with the portion of the pocket intermediate said strips, a suitable receptacle for assembling and arranging the filler 100 in form and quantity best suited to provide a bunch of size and shape desired without undue compression of any part thereof in the final shaping of the cigar.

It should also be noted that the tapered 105 openings in members 16 and 17, obviously will hold filler of less diameter or bulk than the pocket intermediate said members, and consequently if it were attempted to place the same bulk of filler in these tapered 110 openings, the excess bulk would project above the pocket and obstruct the passage

of the roller. In this way the operator is forced to keep the filler within the limits prescribed by said tapered openings and thus any tendency to choke the head or tuck end 5 of the bunch is prevented. This arrangement makes it possible to train, in a much shorter time, the beginner or learner, properly to form the bunch.

Any portions of the filler extending beyond 10 the outer margins of the hook extensions of the forming strips within the pocket may be pushed back, pinched off, or removed and re-distributed within the body of the filler, without waste or scraping any portion 15 thereof.

This method of forming the bunch secures a marked advantage in two respects; it produces a bunch of the exact length required. This obviates the necessity of cutting off the 20 end to secure the required length, as is now the common practice. This saves waste of tobacco, which by cutting becomes scrap, and it also saves labor, both important items in the manufacture of a cigar.

25 Another marked advantage of the arrangement and formation of the adjustable forming strips is the facility provided for securing the proper length of the portion of leaf required to form the binder, that is to say, the said strips being adjusted to the exact length of the bunch desired, the end of the leaf may be placed at the outer margin of one strip, and laid across and torn or severed on the sharp outer margin as at 30 14', of the other strip. Hence waste in connection with the binder is obviated.

As above stated these strips may be adjusted to suit the length of cigars which it is desired to make. Where the adjustment 40 is slight, a little space between the inner margin of the strips and the apron is immaterial so long as the apron does not overlap the margin of the strip. Where the adjustment is substantial or the strips encroach 45 upon the apron to cause overlapping, an apron of required width is substituted.

It should also be understood that different shaped strips may be used interchangeably 50 on the same table to secure the shape of cigar required. For example, where a short sharp taper to the end of the cigar is required, a relatively narrow strip is used, relatively thick at its outside margin, with a sharp bevel or inclination to the inner margin as for example in Fig. 8. Where a long gradual taper is desired a wider strip is used, not so thick at its outer margin with a gradual incline to its inner margin as in Fig. 5, and so on.

60 What I claim is:—

1. In combination with a bunching table having a bunching pocket and bunching apron, members having openings of tapered formation adjustably secured in the pocket 65 and flanking the apron, the margins of said

tapered openings adjacent the apron lying flush with the active surface of the apron.

2. The combination defined in claim 1 in which forming strips are connected with said members and extend over the table and flank 70 the rolling apron, the margins of said strips adjacent the apron being flush with the active surface thereof.

3. The combination defined in claim 2, in which said forming strips are provided with 75 clearly defined upper outer margins as means for measuring and severing the binder from the leaf.

4. In combination with a bunching table and apron, parallel forming strips adjustably secured to the table and flanking the apron, and having surfaces inclined from their outer margins downwardly toward their inner margins to a line flush with the apron and forming in combination with the 80 apron a continuous rolling surface.

5. In combination with a bunching table and apron, interchangeable parallel forming strips adjustably secured to the table and flanking the apron, and having surfaces inclined from their outer margins toward their inner margins 85 to a line flush with the apron and forming in combination with the apron a continuous rolling surface.

6. In combination with a bunching table 90 and apron, substantially parallel strips adjustably secured to the table and flanking the apron and having surfaces inclined from their outer margins toward their inner margins to a line substantially flush with the 100 apron, and having extensions fitting in the pocket of the table and so shaped to give the required formation to the bunch ends.

7. In combination with a bunching table and apron, substantially parallel strips adjustably secured to the table and flanking the apron and having surfaces inclined from their outer margins toward their inner margins 105 to a line substantially flush with the apron and having extensions projecting into the 110 pocket of the table, so shaped as to form tapered ends for the said pocket.

8. In combination with a bunching table and apron, substantially parallel strips adjustably secured to the table and flanking 115 the apron and having surfaces inclined from their outer margins toward their inner margins to a line substantially flush with the apron and having extensions projecting into the 120 pocket of the table, so shaped that the pocket and said extensions form a channel having contracted ends.

9. In combination with a bunching table and apron, substantially parallel strips adjustable on the table and flanking the apron 125 and having surfaces inclined from their outer margins toward their inner margins to a line substantially flush with the apron and having extensions projecting into the 130 pocket of the table, so shaped that the pocket

and said extensions form a channel having contracted ends, or end-openings of substantial conical formation.

10. In combination with a bunching table and apron, relatively adjustable substantially parallel forming strips flanking the apron and having upper outer margins spaced apart a distance corresponding with the dimensions required for the binder and

so formed as to provide means for measuring 10 the binder to be severed from the leaf.

11. The combination defined in claim 10, in which said upper outer margins of the parallel strips provide means also for severing the measured portion of the leaf to form 15 the binder.

BERNARD LIBERMAN.
